UNITED STATES PATENT OFFICE.

ANICETO VISITACION, OF BROOKLYN, NEW YORK.

COMBINATION CHECK PEN PROTECTOR.

Application filed November 12, 1921. Serial No. 514,451.

To all whom it may concern:

Be it known that I, ANICETO VISITACION, a citizen of the United States, and a resident of Brooklyn, in the county of Kings and

State of New York, have invented certain new and useful Improvements in Combination Check Pen Protectors, of which the following is a specification.

One of the objects of this invention is to provide a fountain pen having a check protecting device enclosed within a cap engageable with the pen body.

This and other objects are attained by the novel construction and arrangement of parts hereinafter described and shown in the accompanying drawing, forming a material part of this disclosure, and in which:

Figure 1 is a partial sectional view showing a pen constructed in accordance with the invention.

Figure 2 is a general view of the pen showing one of the ink filling levers and the pen shifting means.

Figure 3 is a partially sectional end view taken on the line 3—3 of Figure 2.

Figure 4 is a similar sectional view taken on the line 4—4 of Figure 1.

Figure 5 is a sectional plan view of the printing wheel taken on line 5—5 of Figure 3.

Referring to the drawing in detail, the numeral 10 designates in general the cylindrical barrel of the holder. A tapered element 11 is frictionally engaged with the lower end of the barrel and a removable cap 12 is frictionally engaged on the upper, slightly tapered outer surface of the barrel.

Interiorly of the cap 12, near its upper end, is arranged a check protecting device comprising a wheel carrying shaft 50, having a knurled operating head 51. The opposite end of the shaft is concentrically recessed to receive the end 52 of an eccentric 54, having a stem 53 in alignment with the part 52.

A retaining disc 55 is secured to the shaft 50, together with a collar 56, on the periphery of which are formed, parallel to the axis of the collar, ten dove tail slots 56', best shown in Figure 5.

Another disc 57, free to rotate on the shaft, is provided with a single slot 58 slightly wider than the slots 56'.

Slidably secured in the slots 56' are plates 60 having raised figures engraved on their convex surfaces.

Adjacent the outer surface of the disc 57 is a webbed wheel 62 arranged to rotate on the eccentric 54 of the stem 53, the wheel having a projecting concentric ring 64 formed integral with its web.

A series of six transverse undercut slots, duplicates of the slots 56', are formed in the periphery of the wheel to receive the printing plates 60 when said plates are passed through the slot 58 of the disc 57.

Below the undercut slots of the wheel 62, are arcuately curved plates 66, the convex sides of which are knurled to impress perforations when rolled along the surface of a check. On that portion of the peripheral edge of the wheel 62, not provided with slots, is a similar knurled section and a single fixed character as the \$ sign, shown in Figure 3.

Engaged about the hub of the wheel 62 is a spring having a plurality of extending elements 68, engaging and pressing outwardly the knurled plates 66.

From Figures 3 and 4 it will be seen that any of the printing plates 60 may be moved into operative position with reference to the \$ sign by manipulating the co-operating parts as follows.

The wheel 62, carrying the \$ sign, is rotated into front or printing position, and the disc 57 is rotated until the slot 58 is in line with one of the knurled plates 66. The collar, carrying the printing plates 60, is turned by the knurled knob 51 until the first desired number is in line with the slot 58 of the disc 57, and the knurled plate 60 is then depressed against the tension of the spring 68, presenting an alined slot through which the proper printing plate may be moved into operative position with relation to the \$ sign. This operation is repeated until all the numbers necessary to print the amount of the check are arranged in printing position.

To provide against any of the unused characters being imprinted on the check, the wheel 62 is caused to be elevated above the general surface of the unused characters, by holding the stem 53 of the eccentric 54; and rotating the wheel 62 relative thereto a small handle 70 being fixed to the stem for this purpose.

An implement for assisting in moving the plates is provided and is shown housed in the pencil element 38 by the numeral 72 of Figure 1. In this figure is also shown an

inking pad 73, held against a ring element 74 by the action of a spring 75, the lower ends of which engage lugs 76 formed with the cap.

5 A semi-spherical cover 80, hinged to the cap 12 as at 80', provides means for closing the cap and preventing dust from clogging the printing mechanism.

10 While certain preferred embodiments of this device have been shown and described, it will be apparent that minor changes in the form, arrangements, proportions, sizes and details may be made without departing from the scope of the invention as defined 15 by the appended claims.

Having thus described my invention, what I claim as new and desire to secure by Letters Patent, is:—

1. A check protector comprising a 20 cylindrical type magazine having type receiving and retaining grooves in its periphery, a printing wheel associated therewith, and means to move the wheel into concentric or eccentric relation to the magazine.

25 2. A check protector comprising a cylindrical type magazine having type receiving and retaining grooves in its periphery, a printing wheel associated with the magazine and an eccentric associated with 30 the wheel to move the same into concentric, and eccentric relation to the magazine.

3. A check protector comprising a cylindrical type magazine having type re-

ceiving and retaining grooves in its periphery, a printing wheel at one end of 35 the magazine, a spacing disk between the magazine and wheel, the printing wheel having peripheral grooves to receive type from the magazine, and an eccentric bearing 40 for the wheel mounted concentrically with the magazine whereby the wheel may be made to rotate eccentrically or concentrically with relation to the magazine.

4. In a check protecting device adapted to be engaged with a writing implement, said device comprising a casing, a sectional shaft passing diametrically through said casing, a collar having transverse slots formed on its periphery fixed to one section of said shaft, type plates slideable in the slots, a 50 printing wheel rotatable on the other section of said shaft, said wheel having transverse slots formed partially around its peripheral face, paper piercing means formed on the remaining periphery of said wheel, said 55 slots providing means for transversely sliding said type plates from the collar to the printing wheel, paper piercing plates contacting with said wheel, spring arms acting against said plates, means for elevating the 60 printing wheel when the type plates are in printing position, and means for closing the casing.

In testimony whereof I have signed my name to this application.

ANICETO VISITACION.
